UNITED STATES PATENT OFFICE.

NAJEEB MALLUK, OF NEW YORK, N. Y.

DESIGN FOR A MIRROR-FRAME.

SPECIFICATION forming part of Design No. 30,330, dated March 14, 1899.

Application filed October 4, 1898. Serial No. 692,648. Term of patent 31 years.

To all whom it may concern:

Be it known that I, NAJEEB MALLUK, a citizen of the United States, and a resident of New York, (Brooklyn,) in the county of Kings and State of New York, have invented and produced a certain new and original Design for a Mirror-Frame, of which the following is a specification, reference being had to the accompanying drawings, forming part thereof.

10 Figure 1 is a plan view of the mirror or picture frame, showing my new design. Fig. 2 is a sectional view taken on the line C D, Fig. 1. Fig. 3 is a sectional view on the line A B, Fig. 1.

15 As shown in the drawings, the leading or material features of my design are the border of a horseshoe-shaped frame, consisting of a series of ribs disposed or arranged as shown in Fig. 1, the said ribs being convex in cross-section, the indentations on either side of the frame within the border containing the pro-

jecting nail-heads in imitation of a horseshoe, and the irregular panel or figure for any suitable name or words at the top intersecting the said ribs. The said panel is slightly 25 raised above the surface of the frame and is formed of intersecting arcs of circles of various diameters disposed as shown. The frame is further provided with an inner border or rim semicircular in cross-section extending 30 completely around the frame.

What I claim as new, and desire to secure by Letters Patent, is—

The design for a mirror-frame as herein shown and described.

Signed at Brooklyn, in the county of Kings and State of New York, this 30th day of September, A. D. 1898.

NAJEEB MALLUK.
